 Matthew W. Mitchell(57) **CLAIM**

The ornamental design for a stethoscope holder, as shown and described.

DESCRIPTION

FIG. 1 is a front, left-side perspective view of a stethoscope holder of the present invention;

FIG. 2 is a front, right side perspective view thereof;

FIG. 3 is a rear, right side perspective view thereof;

FIG. 4 is a rear, left side perspective view thereof;

FIG. 5 is a top view thereof;

FIG. 6 is a right-side view thereof;

FIG. 7 is a left-side view thereof;

FIG. 8 is a rear view thereof; and,

FIG. 9 is a front view thereof.

The broken lines depict portions of the article that form no part of the claimed design.

1 Claim, 9 Drawing Sheets(56)
